UNITED STATES PATENT OFFICE.

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed March 20, 1928. Serial No. 263,118.

My invention relates to railway traffic controlling apparatus, and particularly to apparatus of the type comprising train-carried governing means controlled by train governing energy received from the track rails. More particularly my present invention relates to the trackway portion of such apparatus.

I will describe two forms of trackway apparatus embodying my invention, and will then point out the novel features thereof in claims.

In the accompanying drawing, Fig. 1 is a diagrammatic view showing one form of trackway apparatus embodying my invention. Fig. 2 is a diagrammatic view showing a modification of a portion of the apparatus shown in Fig. 1 and also embodying my invention.

Referring first to Fig. 1, the reference characters 1 and 1^a designate the track rails of a railway track over which traffic moves at times in both directions. These rails are divided by insulated joints 2 into blocks which are made up of main track sections and reset track sections. In the drawing I have illustrated only one block, which block comprises a main section, A—B, a reset section A¹—A at one end of the main section, and a second reset section B—B¹ at the other end of the main section. The first of these reset sections may be termed the "westbound" reset section, and the second may be termed the "eastbound" reset section. Each reset section is comparatively short, and may, for example, be 100 feet to 200 feet in length. Located adjacent the point A¹ is a westbound signal S⁵ and an eastbound signal S². Located adjacent the point B is a westbound signal S³ and an eastbound signal S⁴. Each signal is provided with a signal relay or line relay which is designated by the reference character H with the same exponent as that applied to the associated signal.

The signals are controlled in accordance with what is known in the railway signaling art as absolute permissive block signaling. That is to say, when an eastbound train leaves the first passing siding to the west of point A¹, it opens relays H⁵ and H³, so that signals S⁵ and S³ both change to the stop indication. When the train passes signal S², this signal, of course, assumes the stop indication, and when the train passes signal S⁴, the lat-

ter signal also assumes the stop indication. When a westbound train leaves the next passing siding to the east of point B¹, it de-energizes relays H² and H⁴, but relay H³ remains energized until the train passes signal S⁵ and relay H⁵ remains energized until the train passes signal S⁵. The apparatus for controlling relays H in the manner specified, is omitted from the drawing, because the control of these relays has nothing to do with my present invention.

The reset section A¹—A is constantly supplied with alternating current from a transformer T¹, the primary 3 of which is connected with a transmission line L which in turn is connected with a generator G. The current thus supplied to reset section A¹—A is converted into unidirectional current by a rectifier R¹, and this unidirectional current is supplied to the rails of the main section A—B from which it is taken through a rectifier R² and supplied to the rails of section B—B¹, and so to a track relay C for the block between points A¹ and B¹. The circuit for the secondary of transformer T¹ is from the left-hand terminal of this secondary, through wire 5, rail 1 of reset section A¹—A, wire 6, reactance 7, rectifier R¹, wires 8 and 9, rail 1^a of the main section A—B, wire 54, rectifier R², wire 10, rail 1^a of reset section B—B¹, wires 11 and 12, winding of track relay C, wires 13 and 14, rail 1 of reset section B—B¹, wire 15, reactance 16, rectifier R², reactance 17, rail 1 of main section A—B, wire 18, reactance 19, rectifier R¹, wire 20, rail 1^a of section A¹—A, wire 21, and reactance 22 to the right-hand terminal of the secondary 4 of transformer T¹. It will be seen, therefore, that the terminals of secondary 4 are connected with one end of one rail and the other end of the other rail of section A¹—A, whereas the input terminals of rectifier R¹ are connected with the free ends respectively of the two rails of this section. The output terminals of rectifier R¹ are connected with the two rails of section A—B respectively at the west end of this section. The input terminals of rectifier R² are connected with the two rails respectively of section A—B adjacent the east end of this section, whereas the output terminals of rectifier R² are connected with one end of one rail and the other end of the other rail of section B—B¹. Track relay C is connected

with the free ends respectively of the rails of section B—B¹. It follows that alternating current always flows in one rail of reset section A¹—A even when this section is occupied by a train, and that track relay C, which is of the direct current type, receives unidirectional current when there is no train between signals S⁵ and S³.

When a westbound train is approaching signal S³, relay H² is, of course, de-energized, whereupon alternating train governing current is supplied to the rails of section A—B by a transformer T² if relay H⁵ is energized. The circuit for the primary 55 of this transformer is from the lower line wire L, through wires 23 and 24, back contact 25 of relay H², front contact 26 of relay H⁵, wire 27, primary 55, and wires 28 and 29 to the upper line wire L. The left-hand terminal of secondary 56 of transformer T² is connected with rail 1 by wires 30 and 18, whereas the right-hand terminal of this secondary is connected with rail 1^a through a resistance 31 and wires 32 and 9.

When either relay H³ or H⁴ is de-energized, alternating train governing current is supplied to the primary 57 of a transformer T⁴. When relay H³ is de-energized, the primary circuit for transformer T⁴ is from the lower line wire L, through wire 33, back contact 42 of relay H³, wires 43 and 36, primary 57 and wire 37 to the upper line wire L. When relay H⁴ is de-energized, the circuit is the same except that it includes wire 34 and back contact 35 of relay H⁴. The left-hand terminal of secondary 58 of transformer T⁴ is connected with rail 1^a at the left-hand end of section B—B¹, through wires 38 and 11; the right-hand terminal of secondary 58 is connected with rail 1 at the right-hand end of section B—B¹, through a resistance 40 and wires 39 and 14.

The reference character T³ designates a transformer for supplying train governing current to the main section A—B while an eastbound train is proceeding through this section. The primary circuit for transformer T³ is closed when and only when track relay C is de-energized and relay H⁴ is energized, the circuit then being from secondary 58 of transformer T⁴, through wires 38 and 11, track rail 1^a, wires 10 and 44, primary 45 of transformer T³, wire 46, back contact 47 of relay C, wire 48, front contact 49 of relay H⁴, wire 50, resistance 51, wire 15, rail 1, wires 14 and 39 and resistance 40 to secondary 58 of transformer T⁴. The secondary 52 of transformer T³ is connected across the rails of section A—B, a resistance 53 being interposed between one terminal of this secondary and the rail 1.

Before explaining the operation of the apparatus shown in Fig. 1, it should be pointed out that this apparatus is suitable for co-operation with train-carried governing means requiring the supply of alternating train gov-

erning current to at least one of the track rails to prevent a stop indication of any suitable kind, such as an automatic application of the brakes. If the supply of such current is discontinued, a stop indication will result unless the engineman takes proper action to acknowledge the change in traffic conditions. If he does acknowledge, the train may proceed without incurring a stop indication, but if alternating current is again supplied to the rails occupied by the train and this current is subsequently discontinued, the engineman must again acknowledge to prevent a stop indication. One form of train-carried governing means suitable for co-operation with the trackway apparatus herein disclosed is shown and described in United States Letters Patent, Reissue No. 16,502, granted on December 7, 1926, to Ronald A. McCann, for railway traffic controlling apparatus. In apparatus of the type described in that patent, the train-carried governing means is controlled by alternating current in the track rails through the medium of an inductive receiver mounted on the train in advance of the forward axle, so that it is necessary for the alternating train governing current to flow through at least one track rail in advance of the train in order to prevent an automatic application of the brakes.

The operation of the apparatus shown in Fig. 1, is as follows: I will first assume that an eastbound train passes along the track and that traffic conditions to the east of point B¹ are clear, so that relay H⁴ is energized. As the train leaves the first passing siding to the west of signal S⁵, relays H⁵ and H³ both become de-energized. Relay H⁵ has no effect on the parts of the apparatus shown in the drawing, but the opening of relay H³ causes train governing current to be supplied to transformer T⁴ and so to the rails of reset section B—B¹. As the train enters reset section A¹—A it receives alternating current through rail 1^a and so a clear indication is given aboard the train. Alternating current is now shunted away from rectifier R¹, however, so that track relay C opens. Relay H³ and track relay C both being open, and relay H⁴ being energized, train governing current is supplied from transformer T⁴ to transformer T³ and so to the rails of section A—B, with the result that when the train enters this section it will receive train governing current from both of the track rails and so the proceed indication aboard the train will be continued. When the train enters the reset section B—B¹, it will receive train governing current from rail 1 of this section due to the fact that relay H³ is still open, and so the proceed indication aboard the train will be continued.

Assuming now that a westbound train passes along the track, relays H² and H⁴ will be opened as soon as such train leaves the first

passing siding to the east of point B¹. Assuming that traffic conditions to the west of signal S⁵ are clear, relay H⁵ will be energized, and since relay H² is open, alternating train 5 governing current will be supplied to the primary of transformer T² and so to the rails of section A—B. Alternating current is also supplied to the primary of transformer T⁴, because relay H⁴ is open, and so this current 10 is supplied to the rails of reset section B—B¹. The train will therefore receive a proceed indication throughout the entire block between signals S³ and S⁵.

Reverting now to the movement of an east-bound train, I will assume that as this train 15 approaches signal S², relay H⁴ is open, so that signal S⁴ indicates stop and signal S² indicates caution. The eastbound train will then receive a proceed indication until it passes point A, but upon entering section A—B it 20 will receive a stop indication, because the primary circuit for transformer T³ is now open at front contact 49 of relay H⁴. The engineer must therefore acknowledge the 25 caution indication of signal S² in order to avoid an automatic application of the brakes at point A. Upon entering reset section B—B¹, the train will receive alternating current from rail 1, due to the fact that the primary circuit for transformer T⁴ is closed at 30 both contacts 42 and 35 of relays H³ and H⁴. Upon passing signal S⁴ the supply of alternating current will cease, because of the occupied condition of the track to the east of 35 this signal, with the result that the engineer must again acknowledge in order to avoid an automatic application of the brakes. Assuming now that the main section A—B is occupied, and that an eastbound train passes 40 over the track. Upon passing signal S² the train will receive alternating current from rail 1^a of section A¹—A; but the supply of alternating current will cease as soon as the train enters section A—B, with the result 45 that the engineer must acknowledge in order to avoid an automatic application of the brakes.

Assuming now that signal S⁵ is at stop and that a westbound train passes signal S³, 50 the supply of alternating current will be discontinued at point B, because the primary circuit for transformer T² is open at contact 26 of relay H⁵. Consequently, the engineer must acknowledge the caution indication 55 given by signal S³ in order to avoid a brake application. Upon entering reset section A¹—A, the apparatus on the train will be reset, because of the fact that the train receives alternating current from rail 1, but the 60 supply of alternating current will cease upon passing signal S⁵ and so the engineer must acknowledge the stop indication of this signal in order to avoid a brake application.

It will be observed that alternating current 65 is fed to the reset section A¹—A and is

then converted into unidirectional current to feed the remaining portion of the track circuit for the block between signals S⁵ and S³. Should the supply of alternating current to the rails of the reset section A¹—A fail for 70 any reason, so that this section would be ineffective to reset the locomotive equipment, the defect will cause the track relay C to become de-energized, with the result that signal S³ will assume the stop indication and the 75 next westbound signal in the rear will, of course, indicate caution. Similarly, should anything occur to prevent the supply of alternating current from transformer T⁴ to the 80 rails of reset section B—B¹ the supply of train governing current to transformer T³ would, necessarily, cease, with the result that an eastbound train entering section A—B would receive a stop indication.

Reactance 22 is interposed between transformer T¹ and the track rail 1^a to limit the amount of alternating current flowing from the secondary of this transformer when a train stands in section A¹—A. Reactance 7 is used to limit the amount of alternating current supplied through rectifier R¹ to the remaining portion of the track circuit, so that when the track circuit is not occupied transformer T¹ will furnish only the amount of current necessary to operate track relay C. 90 Reactance 19 is inserted in the output circuit of rectifier R¹ to smooth out the rectified current supplied to the rails of section A—B and to prevent the secondary 56 of transformer T² from being short circuited by rectifier R¹. Resistance 31 is included in the secondary circuit for transformer T² for the usual purpose of limiting the amount of current supplied by this transformer to the track rails when a train occupies section 100 A—B. The purpose of resistance 53 is the same as that of resistance 31. The purpose of reactance 17 is the same as that of reactance 19, and the purpose of reactance 16 is the same as that of reactance 7. The purpose 105 of resistance 51 is to limit the amount of current supplied to the primary of transformer T³ when a train occupies section A—B, and also to prevent shunting rails 1 and 1^a of section B—B¹ at times. Suppose 110 an eastbound train enters section A¹—B¹ with signal H⁴ at clear and then backs out of the section or leaves by a siding switch. Relay C would not be energized due to shunt 15—50—48—46—44—10. Resistance 40 is 115 used to limit the output current of transformer T⁴ when a train occupies section B—B¹.

Referring now to Fig. 2, I have herein illustrated a modification of the apparatus shown at location A in Fig. 1. In Fig. 2 the output circuit for rectifier R¹ passes through the secondary 56 of transformer T², so that one output terminal of the rectifier is connected with rail 1^a through wire 59, and the 125

other output terminal is connected with rail 1 through secondary 56 and wire 60. Rectifier R^1 transforms the alternating current into unidirectional current as before, but this 5 rectifier also functions as a single wave rectifier for the train governing current supplied by transformer T^2 . It follows that the train governing current supplied to section A-B from this transformer will be half 10 waves only, so that the amplitude of this current must be increased to compensate for the fact that one-half of each wave is eliminated. The advantage of the apparatus shown in Fig. 2, is that a failure of the secondary 15 circuit of transformer T^2 will result in failure to energize track relay C, with the result that signal S^3 will indicate stop, and the westbound signal next in the rear will indicate caution.

20 Although I have herein shown and described only two forms of apparatus embodying my invention, it is understood that various changes and modifications may be made therein within the scope of the appended 25 claims without departing from the spirit and scope of my invention.

Having thus described my invention, what I claim is:

1. In combination, a stretch of railway 30 track divided into a main section and a relatively short reset section at each end of the main section, a source of alternating current having its terminals connected with one end of one rail and the other end of the other rail respectively of the first reset section, a 35 rectifier having its input terminals connected respectively with the free ends of the rails of said first reset section, the output terminals of said rectifier being connected with the 40 rails of said main section, a second rectifier having its input terminals connected with the rails of said main section and its output 45 terminals connected with one end of one rail and the other end of the other rail of the second reset section, and a direct current track relay having its terminals connected with the free ends respectively of the rails of said second reset section and operated by the rectified current supplied from said alternating 50 current source.

2. In combination, a stretch of railway 55 track divided into a main section and a relatively short reset section at each end of the main section, a source of alternating current having its terminals connected with one end of one rail and the other end of the other rail respectively of the first reset section, a rectifier having its input terminals connected respectively with the free ends of the rails of 60 said first reset section, the output terminals of said rectifier being connected with the rails of said main section, a second rectifier having its input terminals connected with the rails of said main section and its output 65 terminals connected with one end of one rail and the other end of the other rail of the second reset section, and a direct current track relay having its terminals connected with the free ends respectively of the rails of said second reset section and operated by the rectified current supplied from said alternating 70 current source, means operating when a train occupies or is approaching said second reset section to connect the terminals of a second source of alternating current with the said free ends respectively of said second reset section, means operating when said track relay is open and traffic conditions beyond said sec-

75 rail and the other end of the other rail of the second reset section, and a direct current track relay having its terminals connected with the free ends respectively of the rails of said second reset section and operated by the rectified current supplied from said alternating current source, and means controlled by traffic conditions for supplying alternating train governing current to the rails of said main and second reset sections.

3. In combination, a stretch of railway 80 track divided into a main section and a relatively short reset section at each end of the main section, a source of alternating current having its terminals connected with one end of one rail and the other end of the other rail respectively of the first reset section, a rectifier having its input terminals connected respectively with the free ends of the rails of 85 said first reset section, the output terminals of said rectifier being connected with the rails of said main section, a second rectifier having its input terminals connected with the rails of said main section and its output terminals connected with one end of one rail and the 90 other end of the other rail of the second reset section, and a direct current track relay having its terminals connected with the free ends respectively of the rails of said second reset section and operated by the rectified current supplied from said alternating current source, and means operating when a train occupies or is approaching said second reset section to connect the terminals of a second source of alternating current with the said free ends respectively of said second reset section.

4. In combination, a stretch of railway 95 track divided into a main section and a relatively short reset section at each end of the main section, a source of alternating current having its terminals connected with one end of one rail and the other end of the other rail respectively of the first reset section, a rectifier having its input terminals connected respectively with the free ends of the rails of 100 said first reset section, the output terminals of said rectifier being connected with the rails of said main section, a second rectifier having its input terminals connected with the rails of said main section and its output terminals connected with one end of one rail and the other end of the other rail of the second reset section, and a direct current track relay having its terminals connected with the free ends respectively of the rails of 105 said second reset section and operated by the rectified current supplied from said alternating current source, means operating when a train occupies or is approaching said second reset section to connect the terminals of a second source of alternating current with the said free ends respectively of said second reset section, means operating when said track relay is open and traffic conditions beyond said sec-

ond reset sections are safe to supply alternating current from the first mentioned ends of said second reset section to the rails of said main section, and means controlled by traffic 5 conditions beyond said first reset section for supplying alternating train governing current to the rails of said main section when the main section is occupied.

5. In combination, a stretch of railway 10 track divided into a main section and a relatively short reset section, a source of alternating current having its terminals connected with one end of one rail and the other end of the other rail respectively of said reset 15 section, a rectifier having its input terminals connected respectively with the free ends of the rails of said reset section and having its output terminals connected with the rails of said main section, and a direct current track 20 relay receiving current from the rails of said main section and responsive to the unidirectional current furnished from said source by said rectifier.

6. In combination, a stretch of railway 25 track divided into a main section and a relatively short reset section, a source of alternating current having its terminals connected with one end of one rail and the other end

of the other rail respectively of said reset section, a rectifier having its input terminals 30 connected respectively with the free ends of the rails of said reset section and having its output terminals connected with the rails of said main section, a direct current track relay 35 receiving current from the rails of said main section and responsive to the unidirectional current furnished from said source by said rectifier, and means controlled by traffic conditions for supplying alternating train governing current to the rails of said main section. 40

7. In combination, a stretch of railway track divided into a main section and a relatively short reset section, a source of alternating current connected with the rails of 45 said reset section, a rectifier having its input terminals connected with the rails of said reset section and its output terminals connected with the rails of said main section, and a direct current track relay receiving current 50 from the rails of said main section and responsive to the unidirectional current furnished from said source by said rectifier.

In testimony whereof I affix my signature.

HOWARD A. THOMPSON.
